UNITED STATES PATENT OFFICE

ERNEST W. LETZIG, OF KANSAS CITY, MISSOURI

ADJUSTABLE BODY SUPPORT

Application filed March 31, 1930. Serial No. 440,452.

This invention relates to adjustable body supports for use in caskets whereby the undertaker may elevate the body as close to the top of the casket as desired for exposure during funeral ceremonies and the like, all of the operating parts being readily accessible without disturbing the position of the body, its supporting mattress, or the casket lining.

Although a number of different devices of this general character have been produced, no one, as far as I am aware, has produced a construction providing for all possible adjustments which may be needed in use, as due to physical characteristics of cadavers, difference in girth, etc., it is frequently necessary to provide means whereby one shoulder or one leg may be elevated higher than the other shoulder or leg, or it may be desired to place the torso or the pedal extremities in a plane above or below the other parts of the body, or even to lower the hips and elevate both the shoulders and feet, these adjustments being necessary as caskets are purchased without relation to the girth of the body to be contained therein. The undertaker, therefore, with the device of the invention may accommodate any casket to the size of the body for its best exposure.

The prime object of the present invention, therefore, is to provide a body support having such a degree of flexibility that, if the support extends for the full length of the casket, any quarter of the body may be adjusted independently of the other body sections, so that the undertaker may position the body to the greatest advantage in the casket, it being of course understood that after the ceremony the body and its support are lowered, if desired, into the casket for burial.

Another object of the invention is to provide mechanism which will not decrease the capacity of the casket and which is of such construction that for exhibition purposes to a prospective customer, it is possible to fold back the foot end upon the head end so that the shell may be exhibited entirely free of operating mechanism.

A still further object of the invention is to produce a strong, durable, efficient, simple and inexpensive construction of the character set

forth; and in order that it may be fully understood, reference is to be had to the accompanying drawings, in which:

Figure 1 is a top plan view of a casket shell with the body support of the invention in operative relation thereto. 55

Figure 2 is a side elevation with one side of the casket shell removed from position.

Figure 3 is a view similar to Figure 1, but illustrates an adjustable support for the torso only. 60

Figure 4 is a detail view of the preferred type of support for the head end of the casket shell.

Figure 5 is a detail view of the preferred type of support for the foot end of the casket shell. 65

Figure 6 is a detail of the ends of a cross piece forming a part of the invention.

In the said drawings, where like reference characters identify corresponding parts in all of the figures, 1 indicates a casket shell of generally rectangular shape as common, and secured to the interior side walls of said shell some distance above the bottom thereof and being arranged in pairs at the mid-center of the casket and on the head and foot walls 2 and 3 respectively, are a series of spacing blocks 4, each of said blocks carrying a spaced guide strap 5 by means of screws 6. The guides 5 provide slots for the reception of vertically adjustable supporting straps 7. Each of the straps 7 is provided at its upper end with an operating handle 8 out-turned toward the shell of the casket and therefore overlying the blocks 4 so that the available width and length of the casket shell shall not be materially decreased, and each of said straps is also provided with a series of adjusting notches 9 in one of its side edges, whereby it is possible to vertically adjust the straps by engaging the notches with one of the supporting screws or pins 6. 80 85 90

Resting on the bottom of the casket shell and having its ends, when in normal position, terminating substantially flush with the faces of the mid-center straps 7, is a cross piece 10, each end thereof having a double-bevel 11 and 12, the former extending downwardly and outwardly from the top of the cross piece 100

and the latter upwardly and inwardly from the bottom of the cross-piece. Inserted in the ends of the cross-piece 10 and projecting through the bevel 11 are pins 13 reinforced with L-shaped stirrups 14 secured to the under side of the cross piece, said pins passing through a large opening 15 in the lower ends of their respective straps 7. With this construction it will be evident that either end 10 of the cross piece 10 may be raised, the straps 7 remaining substantially vertical, as the bevel 11 and enlarged openings 15 will accommodate the arcuate movement of the cross-piece, so that the ends will not engage 15 and jamb against the side walls of the casket shell.

Extending from head end 2 of the casket shell and having their extremities terminating substantially flush with the inside 20 faces of the head supporting straps 7 are a pair of supporting head-bars 16 having their opposite ends hingedly connected as at 17 to the cross-piece 10. The free ends of the supporting head-straps are provided with enlarged openings 18 engaging pins 19, reinforced by stirrups 20, projecting from the ends of the head-bars 16 substantially as described in connection with the straps 7 at 25 the ends of the cross-piece 10. With this construction it will be evident that the bars 16 may be adjusted to the desired angular relation and that their supporting straps will remain substantially vertical.

Arranged in alignment with each of the 30 bars 16 are a pair of foot-bars 21, said head and foot alined bars being hingedly connected together as at 22. The free ends of the foot bars 21 terminate, when in normal position, substantially flush with the inside faces 40 of the adjustable foot-supporting straps 7, but, as under certain conditions it is desirable to remove all operating mechanism on the foot end of the casket for exhibition to a prospective purchaser, the foot-straps 7 are 45 provided at their lower ends with keyhole openings 23 for detachable engagement with headed pins 24 projecting from the ends of the foot-bars 21. The adjustment of said bars is otherwise similar in all respects to 50 the adjustment of the other parts of the mechanism.

The spaced alined bars are connected together by flexible cross webs 25 to provide 55 a support for a mattress 26, making it possible to independently adjust any quarter of a body through the independent adjustment of any or all of the points of support, so that the undertaker may conveniently and 60 easily adjust a body for exhibition purposes without the necessity of disturbing the body, its mattress or the lining of the casket (not shown).

In order to overcome any possible tendency 65 of the entire body support moving toward the foot end of the casket due to the

fact that the preponderating load is at the head end thereof, the inner faces of the casket shell, at substantially their mid line, are provided with vertically-extending stops 70 27 in position for abutment with the cross-piece 10, whereby any possible movement toward the foot is entirely prevented.

In Figure 3 a half length or torso body support is indicated, such construction corresponding in all details with that above described, except that the foot-bars are entirely omitted. This construction is used in the type of casket in which the head end only 75 is open for exhibition at the burial services.

From the above description, it will be apparent that while I have produced a construction embodying all the features of advantage set forth as desirable, it is to be understood that I reserve the right to make all changes properly falling within the spirit 80 and scope of the appended claims and the condition of the prior art.

I claim:

1. The combination with a casket shell, of a body support comprising a pair of bars, 90 each pair being arranged in two hingedly connected sections, extending lengthwise of the casket shell and within the same, flexible connections extending crosswise of said casket shell and secured at their opposite ends 95 to said bars to permit the bars on opposite sides of the shell to move independently of each other, and means interconnecting the opposite ends of said bars and casket shell for effecting independent vertical adjustment of the ends of said bars. 100

2. The combination with a casket shell, of a body support comprising a pair of bars extending lengthwise of the casket shell and within the same, each of said bars being divided into two sections hingedly connected together, and means interconnecting the hinged ends of said bars, said means being independently vertically adjustable at its opposite ends. 105

3. The combination with a casket shell, of a body support comprising a pair of bars extending lengthwise of the casket shell and within the same, flexible connections extending crosswise of said casket shell and secured 115 at their opposite ends to said bars, rigid straps loosely connected to the ends of said bars and having a series of locking notches, and pins carried by said casket shell for cooperating engagement with the locking 120 notches of said straps for effecting independent adjustment of the ends of said bars.

4. The combination with a casket shell, of a body support comprising a pair of bars extending lengthwise of the casket shell and within the same, each of said bars being divided into two sections hingedly connected together, means interconnecting the hinged ends of said bars, said means being independently vertically adjustable at its oppo- 125 130

site ends, and means for effecting independent adjustment of the free ends of said bar sections.

5. The combination with a casket shell, of a body support comprising a pair of similar bars adjacent opposite sides of the casket and having their ends adapted for independent vertical adjustments along the adjacent ends of the casket shell, a cross member underlying the other ends of said bars to which the bars are hingedly connected, a second pair of bars arranged in alinement with the hinged bars and hingedly secured thereto, and means for independently vertically adjusting the free ends of said second pair of bars with respect to the end of the casket wall adjacent thereto.

6. The combination with a casket shell, of a body support comprising a pair of bars extending longitudinally of the casket shell and within the same, each of said bars being divided into two hingedly connected sections, a cross member interconnecting the hinged ends of said bars and extending transversely of the casket shell, and means at the opposite ends of said cross member for effecting vertical adjustment of either end thereof with respect to the side walls of the casket adjacent thereto.

30 In testimony whereof I affix my signature.
ERNEST W. LETZIG.
